UNITED STATES PATENT OFFICE.

ARTHUR GEORGE KENT-JOHNSTON, OF BALHAM, LONDON, ENGLAND.

GAS LIGHTING AND EXTINGUISHING APPARATUS.

1,107,962.

Specification of Letters Patent. Patented Aug. 18, 1914.

Application filed February 10, 1914. Serial No. 817,813.

To all whom it may concern:

Be it known that I, ARTHUR GEORGE KENT-JOHNSTON, a subject of the King of Great Britain and Ireland, and residing at "Gleneldon," Thurleigh Road, Balham, London, S. W., England, have invented certain new and useful Improvements in Gas Lighting and Extinguishing Apparatus, of which the following is a specification.

10 This invention relates to gas lighting and extinguishing apparatus and particularly to apparatus of the type in which a pressure sensitive member such as a diaphragm or bell dividing a gas-tight chamber into two 15 compartments connected by a small orifice is, as the result of being subjected on one side to a sudden increase in the pressure of the gas in the supply mains, caused to operate means controlling the supply of gas to a 20 main and a by-pass burner respectively.

The object of the present invention is to 25 reduce the resistance offered to the initial movement of the pressure member on account of excessive compression of the gas on one side thereof, and to do so in such a manner that not only is the apparatus consequently rendered operable by a much smaller pressure increase but also rendered more reliable in action than hitherto.

30 The invention consists in an apparatus of the above type in which a valve opened during the initial movement of the pressure sensitive member permits the gas in the compartment remote from the gas mains to be 35 displaced into a conduit which is so situated with respect to the main and by-pass burners that the issuing gas is ignited, and thereby utilized to prevent extinction of both burners through either having been extinguished before the other is ignited.

Referring now to the accompanying drawings, Figure 1 is a central vertical section of an apparatus according to the present invention, the valve mechanism, however, being 45 shown in outside elevation. Fig. 2 is a rear view, and Fig. 3 a side view of the valve mechanism shown in Fig. 1, while Fig. 4 is a central vertical section of a modified construction of the apparatus. Figs. 5 and 6 are 50 views showing the valve mechanism in two different positions, and Fig. 7 a plan of the body member of the apparatus with all the upper mechanism and parts removed.

In carrying the invention into effect according to the construction shown in Figs. 1, 2 and 3, a body member, 1, is provided

with an upwardly-extending cylindrical wall, 2, which co-acts with the inner surface of a casing, 3, to form an annular space, 4, into which a liquid, preferably mercury, is introduced through an inlet, 5, so as to form a seal for a bell, 6, dividing the space within said casing into two compartments, 7 and 8. Into the latter of these gas from the mains is admitted through an opening, 9, and passes from the compartment, 8, into the compartment, 7, by way of a small orifice, 10, in the bell, 6, this orifice being of such dimensions as to render the bell sensitive only to sudden increases of pressure in the gas mains, but remain uninfluenced by a gradual increase of pressure. Attached to the bell, 6, by a nut, 11, is a spindle 12, which passes freely through a cross bar, 13, supported on two vertical pillars, 14. At its lower end the spindle, 12, carries a cross bar, 15, through the extremities of which the two pillars, 14, pass, and thereby serve as guides when the bell, 6, moves vertically, while surrounding the spindle, 12, is a sleeve, 16, which is movable relatively to the spindle, 12, and is guided by cross bars, 17 and 18, through which the pillars, 14, also pass. The lower cross bar, 18, is maintained a short distance above a base plate, 19, by an adjustable screw, 20 in order thereby to provide a suitable clearance between the cross bars, 15 and 18, and so prevent accidental operation of the apparatus through vibration or other like causes. The upper cross bar, 17, carries a pawl, 21 (see Figs. 2 and 3) adapted to engage in turn with each of eight teeth on a ratchet wheel, 22, which is connected by a shaft, 23 (see Fig. 3) to the disk, 24, of a disk valve by which the supply of gas to a main and a by-pass burner is controlled. As shown in Fig. 2 the disk 24 contains four equi-distant holes, 25, and by means of a spring, 26, is pressed against the stationary valve part 27 on the face of which there terminate two passages, 28 and 29, in such a position that when, as the result of successive upward movements of the bell 6, the disk 24 is rotated by engagement of the pawl 21 with the ratchet wheel 22, the passages, 28 and 29, shall be alternately placed in communication with the compartment 8 within the bell. The passage 28 is continued through the body member 1 of the apparatus to a conduit, 30, by which the gas passes to the main burner, while the other passage, 29, communicates in a similar way with the

conduit, 31, conveying gas to the by-pass burner. For the purpose of enabling the disk valve to be operated independently of the gas pressure, a projecting rod, 32 on the 5 cross bar, 18, (see Fig. 3) enables the sleeve, 16, and the pawl, 21, carried thereby, to be moved upward by the inward movement of a rod, 33, accessible from the exterior of the apparatus. On the upper side of the bell, 6, there is attached to the nut, 11, by means 10 of a pin, 34, shown in Fig. 3, a pawl, 35, having a screw, 36, by which the position of a ledge 37 and an arm 38 on the pawl can be adjusted relatively to a hollow spindle 39. 15 The passage through the latter terminates in transverse passages below the surface of contact of the movable part 40 of a valve with its seating 41, so that when the valve is open gas passes from the compartment 7 to a 20 chamber 42. By contacting with the arm 38 of the pawl 35 a conical surface 43 at the lower end of the seating 41 causes the pawl 35 to be disengaged from the valve spindle 39, thereby allowing the valve to close by 25 gravity and shut off communication between the compartment 7 and the chamber 42. A conduit 44 connects the chamber 42 with the conduit 21 through which gas normally passes to the by-pass burner. By means of 30 a pipe 45 the compartment 7 is placed in communication with a capacity chamber 46 formed by the coöperation of an outer vessel 47 and an inner concentric vessel 48 with a liquid seal 49. A removable plate or window 50 by which the inside of the apparatus 35 can be inspected, and a removable plug 51 for relieving the pressure in the chamber 7 are also provided. When an apparatus thus 40 constructed is in operation a change of the gas pressure in the mains has no effect on the bell 6 if the change is so gradual that the 45 gas pressures in the compartments 7 and 8 can become equal. On the other hand, if the change of pressure is sudden, as when it is 50 desired to extinguish one burner and ignite the other, a difference of pressure is established between the compartments, 7 and 8, with the result that the bell 6 moves upward, the resistance to this movement being greatly 55 reduced by virtue of the capacity chamber 46 and the consequent change in the level of the liquid therein. As a result the ledge 37 of the pawl 35 comes into contact with the valve spindle 39, and then lifts the valve 40 60 off its seat. The gas pressure within the compartment 7 is at once relieved and the gas allowed to pass through the conduit 44 to the by-pass burner, where it is ignited by the flame from the burner which is then 65 lighted. By the continued upward movement of the bell 6 the sleeve 16 causes the pawl 21 to rotate the ratchet wheel 22 through one-eighth of a revolution. The supply of gas is thereby changed over from 70 one burner to the other, but as the temporary

flame of the gas escaping from the compartment 7 exists at this moment it prevents failure of the apparatus through the one burner being extinguished before the other has been ignited. On the arm 38 of the pawl 70 35, however, coming into contact with the conical surface 43, the pawl 35 is disengaged from the valve spindle with the result that the valve 40 closes by gravity, after which the bell 6 gradually sinks as a result of the 75 pressures of the gas in the compartments 7 and 8 becoming equalized by virtue of the communicating orifice 10.

When an apparatus of this kind is to be employed for the purpose of controlling the supply of gas to more than one main burner, it is modified as shown in Figs. 4, 5, 6 and 7, in the case where the gas is being supplied to two main burners, the apparatus being substantially similar to that already described, with the exception of the valve mechanism. This consists in a disk valve, the disk 52 of which is rotated as before by engagement of a pawl 53, in this case directly carried by the spindle 12, with a ratchet wheel 54. The disk 52 and ratchet wheel 54 are situated, however, on the same side of the stationary valve part 27, the disk being cut away so as to leave two quadrants and the ratchet wheel having six teeth. Terminating on the face of the valve part 27 are three passages, 55, 56 and 57. Of these the passage 55 extends through the body member 1, as shown in Fig. 7, to the conduit 58, by which gas is supplied to one of the main burners, while the passage 56 similarly leads to the conduit 59 of the other main burner. The remaining passage 57 is that by which gas is conducted to the conduit 60 of the by-pass burner. The result of three consecutive upward movements of the bell 6 is illustrated in Figs. 4, 5 and 6, in the first of which the valve disk 52 is in the position in which gas can pass through both passages 55 and 56 to the two main burners, the by-pass passage 57 being closed. In Fig. 5, the passage 56 has been closed by rotation of the disks 52, so that gas can only flow to the main burner through the passage 55 and to the by-pass burner through the 100 passage 57, while in Fig. 6 both passages 55 and 56 have been closed, and gas can only flow by way of the passage 57 to the by-pass burner. In this case the by-pass conduit 60 is divided into two branch conduits 61, leading to the by-pass burners of the two main burners, while the conduit 44 branches into the conduit 60 in such a position that the gas escaping from the compartment 7 is conducted to both the by-pass burners. In this way the production of a flame at the time when the supply of gas is being changed over from one burner to another insures that the corresponding by-pass or main burner 105 shall be ignited, and therefore avoids the 110

risk of failure through one burner being extinguished before ignition of the other has taken place. A capacity chamber is also preferably employed in connection with this modified form of the apparatus.

It will be seen that the invention may be applied to cases where the apparatus is adapted to control the supply of gas to a cluster of burners, any one or more of which 10 may require to be extinguished at will and their by-passes left burning.

Having now described my invention, what I claim as new and desire to secure by Letters Patent is:—

15 1. Gas lighting and extinguishing apparatus comprising in combination a casing, a pressure-sensitive member dividing the space therein into two compartments, to one of which gas is admitted and passes therefrom through a small orifice into the other compartment, main and by-pass burners, valve means operated by said pressure member to control the supply of gas to the burners, a relief valve preventing excessive gas compression in the compartment remote from the gas inlet during initial movement of the pressure member, and means by which the gas passing through said relief valve is utilized to prevent failure of the apparatus 25 through one of the burners being accidentally extinguished before its corresponding by-pass has been ignited, and through a by-pass being extinguished before its corresponding main burner has been ignited.

30 2. Gas lighting and extinguishing apparatus comprising in combination main and by-pass burners, a casing, a pressure-sensitive member dividing the space therein into two compartments, gas inlet means to one of said compartments and a communicating orifice admitting said gas into the other compartment, valve means operated by said pressure member to control the supply of gas to the burners, a capacity chamber in communication with the compartment on the side of the pressure member remote from the gas inlet mains, a relief valve preventing excessive gas compression in the latter compartment during initial movement of the pressure 35 member, and means by which the gas passing through said relief valve is utilized to prevent failure of the apparatus through one of the burners being accidentally extinguished before its corresponding by-pass has 40 been ignited, and conversely.

3. Gas lighting and extinguishing apparatus comprising in combination main and by-pass burners, a casing, a pressure-sensitive member dividing the space therein into two compartments, inlet means admitting gas to one of said compartments and a small orifice allowing said gas to pass gradually into the other compartment, valve means operated by said pressure member to control 45 the supply of gas to the burners, a gravity

closed valve adapted to relieve the pressure of the gas in the compartment remote from the inlet means during movement of the pressure member, a one-way connection between said pressure member and the gravity valve, and a conduit by which the gas passing through the relief valve is conducted to the by-pass burners during the initial movement of the pressure-sensitive member.

4. Gas lighting and extinguishing apparatus comprising in combination a main burner and a by-pass burner, a casing divided into two compartments by a liquid sealed bell, inlet means admitting gas to the compartment within said bell, a small orifice in the bell permitting the gas to pass gradually into the compartment exterior to the bell, valve means connected to said bell to control the supply of gas to the main and to the by-pass burner, a gravity closed valve adapted to permit escape of gas from the compartment on the exterior of the bell, a one-way connection carried by said bell and engaging with said valve during the initial movement of the bell, and a conduit by which the gas passing through said valve is conducted to the by-pass burner whereby, on the supply of gas being changed over from one burner to the other, failure of the device is prevented through one of the burners being accidentally extinguished before the other is ignited.

5. Gas lighting and extinguishing apparatus comprising in combination a main burner and a by-pass burner, a casing, a liquid sealed bell dividing the space therein into two compartments, inlet means admitting gas to the compartment within the bell, and an orifice in the bell through which the gas is permitted to pass gradually into the compartment exterior to the bell, a capacity chamber in communication with the latter compartment within the casing, a disk valve controlling the supply of gas to both burners, and means by which said valve is operated during the upward movement of the bell, a relief valve opened by the bell during upward movement thereof to prevent excessive gas compression in the compartment exterior to the bell, and a conduit by which the escaping gas is conducted to a by-pass burner in order thereby to provide a flame which shall prevent failure of the apparatus through one burner being accidentally extinguished before the other is ignited when the supply of gas is being changed over from one burner to the other.

6. Gas lighting and extinguishing apparatus comprising in combination a main burner and a by-pass burner, a casing, a liquid sealed bell dividing said casing into two compartments, inlet means admitting gas to the compartment within the bell, a small orifice in the bell permitting such gas to pass gradually into the compartment

above the bell, a disk valve controlling the supply of gas to both burners, connecting means between said valve and the bell by which successive upward movements of the latter due to sudden pressure increases of the gas cause the gas to be supplied to the burners alternately, a valve relieving the pressure of the gas in the compartment above the bell during upward movement of the latter, a one-way connection carried by said bell to engage with the valve during upward movement of the bell, and a conduit by which the gas passing through said valve is conducted to the by-pass burner.

7. Gas lighting and extinguishing apparatus comprising in combination a main burner and a by-pass burner; a casing, a liquid sealed bell dividing said casing into two compartments, inlet means admitting gas to the compartment within the bell, a small orifice in the bell permitting such gas to pass gradually into the compartment above the bell, a disk valve controlling the supply of gas to both burners, connecting means between said valve and the bell by which successive upward movements of the latter due to sudden pressure increases of the gas cause the gas to be supplied to the burners alternately, means by which said disk valve can be operated from the exterior of the apparatus independently of the gas pressure, a valve relieving the pressure of the gas in the compartment above the bell during upward movement of the latter, a one-way connection carried by said bell to engage with the valve during upward movement of the bell, and a conduit by which

gas passing through said valve is conducted to the by-pass burner.

8. Gas lighting and extinguishing apparatus comprising in combination a plurality of main burners and a plurality of by-pass burners, a casing, a liquid sealed bell dividing the space within said casing into two compartments, inlet means admitting gas to the compartment within the bell, a small orifice in the bell permitting said gas to pass into the compartment above the bell, a disk valve controlling the supply of gas to all the burners, connecting means between said valve and the bell by which the former is enabled to shut off the supply of gas to the main burners consecutively with successive increases in the gas pressure, while simultaneously admitting gas to the corresponding by-pass burners, a relief valve preventing excessive compression of the gas in the compartment above the bell during the upward movement of the latter, a one-way connection between the bell and said valve, and a conduit conducting the gas passing through said valve to the by-pass burners, whereby there is provided a flame of gas preventing accidental failure of the apparatus at each upward movement of the bell.

In testimony whereof I have signed my name to this specification in the presence of two subscribing witnesses.

ARTHUR GEORGE KENT-JOHNSTON.
